UNITED STATES PATENT OFFICE

PETE PALUMBO, OF WEIRTON, WEST VIRGINIA

CLOTHES DRIER

Application filed April 14, 1930. Serial No. 444,218.

The object of this, my present invention is the provision of a simple apparatus whereby washed clothes may be dried in an easy, convenient and expeditious manner.

5 A further object is the provision of a drying apparatus for damp washed clothes of a construction whereby the clothes may be subjected to heat and to a rapid rotary motion for aerating the clothes so that the same can 10 be expeditiously dried.

A still further object is the provision of an apparatus for this purpose in which the heating element therefor is effectively prevented from contact with the damp clothes, wherein 15 the receptacle for the damp clothes is arranged in a casing that has associated therewith a basin whereby drainage from the clothes may be received therein, wherein the casing is rotated by an electric motor and 20 wherein the current for the motor serves to heat the heating element.

The invention will be fully and comprehensively understood from a consideration of the following detailed description when read in 25 connection with the accompanying drawings which form part of the application, with the understanding, however, that the improvement is capable of extended application and is not confined to the exact showing of the 30 drawings nor to the precise construction described and, therefore, such changes and modifications may be made therefrom as do not affect the spirit of the invention nor exceed the scope thereof as expressed in the 35 appended claim.

In the drawings:

Figure 1 is a substantially central longitudinal sectional view through a clothes drier in accordance with this invention.

40 Figure 2 is a horizontal sectional view approximately on the line 2-2 of Figure 1.

Figure 3 is a diagrammatic view of the electric wiring.

45 My improvement contemplates the employment of a preferably metal casing 1 supported by legs 2 that afford a stand for the casing. The top of the casing 1 is partly open but this open portion is closed by a hinged and flanged door 3. The closed bottom of the casing 1 is provided with a water

outlet opening 4 that registers with a similar opening in a catch basin 5, the basin 5 having an opening in the bottom thereof whose passage is controlled by a hand operated valve or cock 6.

55 From the upper portions of the legs 2 there extend inwardly directed downwardly inclined brace plates 7 that have their lower ends inwardly directed and their said ends secured to discs or like elements 8, respectively, the said elements being disposed upon the opposite faces of the ends of the braces and the upper element 8 is formed with and has secured thereto an upstanding annular flange 9. This flange receives therein the 60 lower end of a tubular shaft 10. The shaft passes through the bottom of the casing 1 and through a bearing block 11 which is fixed in and to the bottom of the casing. The bearing block has a central hub extension 65 formed with an annular groove that provides a raceway for anti-frictional balls 12. The upper end or hollow shaft is screwed or otherwise secured in the hub or boss portion 13 of a disc 14 and the said boss 70 13 has its outer face provided with an annular groove that affords the second raceway for the anti-frictional balls 12. The disc 14 is bolted or otherwise secured to and surrounds an opening in the center of the 75 bottom 15 of the clothes receptacle. The casing 1 is round in plan as is the clothes receptacle. The sides 16 of the clothes receptacle are formed with any desired number of apertures 17 that afford air inlets 80 thereto. The inner face of the clothes receptacle 16, at the bottom thereof, has arranged thereon a reticulated facing 18 which is preferably in the nature of a wire mesh. This mesh prevents the clothes when 85 arranged in the receptacle from clogging the openings 17 and likewise affords a roughened inner face for the receptacle against which the clothes, when the receptacle is revolved 90 will contact and thereby assist in wringing 95 water from the damp clothes and effect in the quick drying of the clothes.

Received through the hollow or tubular shaft 10 there is a tube 19. This tube enters the receptacle 16 and has secured on 100

its upper end in any desired or suitable manner the core 20 of the heating element. The core is of both heat absorbing and diffusing material and is round in cross section. 5 The core has fixed on its outer face a continuous thin wire or filament 21 sustained thereon by suitable headed pins. Conductor wires 22 arranged in suitable insulator sheaths or casings are connected to certain 10 of the metal pins, the said conductors being received through lateral openings in the upper or top portion of the tube 19 and directed through the tube and likewise directed through one of the legs 2 and have 15 their ends connected to a switch 23. The wires from the switch 23 lead directly to the supply wires 24 (diagram Figure 3).

Supported on the bottom of the casing 1 there is the housing 25 for an electric motor. 20 The shaft of the motor has fixed thereon a pinion 26 that is in mesh with a gear wheel 27 removably and adjustably secured on the hollow shaft 10. The circuit wires 24 lead to the motor and are controlled by a suitable 25 switch 28 attached to the leg 2 of the stand. By throwing this switch the current from the battery circuit will be conducted to the motor. The filaments 21 are in the nature 30 of a resistance coil and the switch 23 can be formed to engage with either of the contacts (disclosed by the diagram Fig. 3) to regulate the supply of current directed to the heater while the motor is still in operation.

It is desirable that the heater be arranged 35 at different elevations in the receptacle, and, therefore, I thread the lower end of the said heater and screw thereon an inner nut 29 which is arranged between the discs or plates 8 and an outer nut 30 which contacts with 40 the lower plate. Both nuts are accessible to an operator provided with a suitable wrench and by this simple means, desired vertical adjustment of the heater may be attained. In order to protect the clothes in the receptacle from contact with the cores in the heater the latter is surrounded by a cylindrical reticulated guard 31. The guard is provided 45 on its lower end with depending fingers 32 that pass through suitable openings in the bottom 15 of the receptacle 16.

To further protect the heater the same is enclosed in a cap-like metal shield 33, the tubular side of the shield being provided, adjacent its top, with threaded openings through 55 which are passed binding elements in the nature of bolts 34 that contact with the heater. The cylindrical body of the shield is formed with spaced elongated slots or openings 35 which are preferably of a length corresponding with that of the looped filament wire 21.

With my improvement it will be apparent 60 that water from the damp and washed clothes which are received in the receptacle 16 will pass through the openings 17 and will be directed through the opening 4 into the catch

basin 5. The heater is first brought into use so that the clothes in the receptacle are heated before the motor is turned on. The motor will impart a rapid turning to the receptacle, subjecting the clothes therein to centrifugal 70 action between the guard 31 and the mesh facing 18 for the receptacle, so that the clothes will be thoroughly dried in an easy and expeditious manner. In order to hold the tube 19 properly positioned I arrange therearound 75 a washer 36 which is received in a depression in the upper face of the disc 14 so that the tube and consequently the heating element are held stationary when the receptacle is revolved.

With my improvement the clothes are dried at a small expenditure, as only a limited quantity of electric current is required in the drying operation. The heating element in the tube therefor may be removed by drawing 85 the same outwardly after the nut 30 is moved off of the threaded end of the tube 19 and the nut 29 turned to permit of the tube 19 being raised thereabove. The guard may be readily removed by simply moving the same out 90 of the receptacle and through the open top of the casing and in a like manner the receptacle can be removed from the casing by loosening the binding element 37 between the gear wheel 27 and the hollow shaft 10.

It is believed the foregoing description will fully set forth my construction, operation and advantages thereof to those skilled in the art to which such invention relates so that further detailed description will not be required.

Having described the invention, I claim: A clothes drying apparatus including a casing having an open top and a door for closing the same, having its bottom provided 105 with an opening, a catch basin below the opening having a valve controlling the outlet thereof, a stand providing a support for the basin and having angle downwardly inclined brace plates, upper and lower discs fixed on 110 the confronting ends of the brace plates and the upper discs having an annular flange, a hollow shaft having its lower end received in the flange, passing through the casing, an apertured and cylindrical receptacle to which the upper end of the shaft is fixed, anti-frictional bearings between the bottom of the receptacle and the bottom of the casing, a tubular member extending through the hollow shaft and entering the receptacle, means for 115 vertically adjusting the tubular member, a heater including a core on which the upper end of the tubular member is fixed and said heater having filament wires threaded over the outer face thereof, a cap shield removably and adjustably secured to the core of the heater, conductor wires for the filaments of the heater directed through the tube and to an electric current, a switch controlling the current to the heater, a guard in the re-

ceptacle surrounding the heater, an electric motor wired in the current, a switch controlling the flow of current to the motor and intermeshing means between the shaft of the motor and the tubular shaft for revolving the latter.

In testimony whereof I affix my signature.
PETE PALUMBO.
